CLAIM

The ornamental design for capsule storage holder, as shown and described.

DESCRIPTION

FIG. 1 is a first perspective view of a capsule storage holder; FIG. 2 is a front elevational view thereof; FIG. 3 is a back elevational view thereof; FIG. 4 is a first side elevation view thereof; FIG. 5 is a second side elevation view thereof; FIG. 6 is a top plan view thereof; FIG. 7 is a bottom plan view thereof; FIG. 8 is a back perspective view of the capsule storage holder in an environmental use; and, FIG. 9 is a front perspective of the capsule storage holder in an environmental use. The broken lines showing capsules in FIGS. 8 and 9 represent environment and form no part of the claimed design.

1 Claim, 7 Drawing Sheets
